OF D 16,227

DESIGN.

—o—
F. MANKEY.

PANEL.

No. 16,227.

Patented Sept. 8, 1885.

UNITED STATES PATENT OFFICE.

FREDERICK MANKEY, OF WILLIAMSPORT, PENNSYLVANIA.

DESIGN FOR A PANEL.

SPECIFICATION forming part of Design No. 16,227, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for Open-Work Panels, of which the following is a specification, reference being had to the accompanying photographs, forming part hereof.

My design consists in the figures A, each in the shape of a mutilated ellipse, disposed in rows in the direction of their major axes—longitudinally the panel. Short bars B appear between the figures of each longitudinal row, and short transverse bars C between the

figures of one row and the corresponding figures of the next adjacent row. Openings D lie between said figures. On the upper side of each figure is a rectangular longitudinal elevation, E.

I claim—

The design for an open-work panel, substantially as herein shown and described, consisting in the figures A, bars B and C, openings D, and elevations E.

FREDERICK MANKEY.
